(57) **CLAIM**

The ornamental design for a glass attachment for a portable vaporization device, as shown and described.

DESCRIPTION

FIG. 1 is a front perspective view of the glass attachment for a portable vaporization device;

FIG. 2 is another front perspective view thereof;

FIG. 3 is a front view thereof;

FIG. 4 is a rear view thereof;

FIG. 5 is a side view thereof;

FIG. 6 is an opposite side view thereof;

FIG. 7 is a top view thereof; and,

FIG. 8 is a bottom view thereof.

The broken lines depicted in the drawings are directed to environment and are for illustrative purposes only; the broken lines form no part of the claimed design. The dot-dash broken lines in FIG. 7 depict portions of the glass attachment for a portable vaporization device that form no part of the claimed design.

1 Claim, 6 Drawing Sheets
